(57) **CLAIM**

The ornamental design for a handset, as shown and described.

DESCRIPTION

FIG. 1 is a bottom plan view of a handset showing our new design;

FIG. 2 is a right side view thereof;

FIG. 3 is a front view thereof;

FIG. 4 is a left side view thereof;

FIG. 5 is a top plan view thereof;

FIG. 6 is a rear view thereof;

FIG. 7 is a perspective front view thereof; and,

FIG. 8 is a perspective rear view thereof.

The broken line showing of the environmental structure of the handset in the figures is for illustrative purposes only and forms no portion of the claimed design.
